UNITED STATES PATENT OFFICE.

SPENCER OTIS, OF CHICAGO, ILLINOIS.

RAILWAY COALING TERMINAL.

Application filed December 17, 1921. Serial No. 522,979.

To all whom it may concern:

Be it known that I, SPENCER OTIS, a citizen of the United States, residing at Chicago, in the county of Cook and State of Illinois, have invented certain new and useful Improvements in Railway Coaling Terminals, of which the following is a specification.

The primary object of the invention is to provide a coaling plant of improved 10 construction and arrangement, which, while occupying a minimum of ground area, will instantly and with no cost for power, receive and safely store in bulk, tonnage of coal required to meet demands 15 over protracted periods of time; also instantly and without cost for power deliver any required number of sub-divided charges of such coal, of pre-measured volume to as many different locomotive tenders or other 20 vehicles through which the coal is made available at places of consumption; and permit, at the will of the operatives, at convenient times and with economy in the expenditure of power, the selective replenishment of sub- 25 divided and measured charges so that they will be kept ready for such delivery.

Another object of the invention is to provide means whereby in a plant arranged as aforesaid, the measurement of the sub-divided 30 charges may be ascertained in terms of weight by weighing the coal in transit between the bulk storage space and the containers of the sub-divided charges permitting a record to be kept in terms of weight, 35 of coal delivered to different vehicles.

In carrying out the invention, dump car trackage is provided and beneath this trackage a storage bunker with the capacity equivalent to the total bulk required to be 40 stored and of a construction which permits the coal to be submerged in water and thus protected not only from spontaneous combustion, but from external ignition and thereby admitting of the passage of locomotives over the dump car trackage both for drawing dump cars to the point of discharge and for filling the tenders of locomotives in case it becomes necessary at any one time to increase the charging capacity beyond that 45 of the means for delivering the pre-measured sub-divided charges; supports, for instance in the form of structural framing arises from the sides of the storage bunker and therefore, on either side of the dump car trackage and upon this framing, are mounted, at successive elevations, first a series of

pockets of selected capacity to receive and hold the pre-measured charges of coal at an elevation which permits of automatic and instant delivery by gravity into tenders or other vehicles passing beneath the pockets and along side the framing, and secondly, above said pockets, trackage for a bridge crane having a bucket, for instance, a clam-shell bucket, which permits it to elevate 65 coal; said crane by its novel functioning of picking up, elevating, traversing of the bridge upon its trackage and traversing the trolley upon the bridge to selected position of pick up and deposit being adapted to 70 serve the purposes of picking up coal from the bunker and depositing it in any one of the several pockets, selectively, and picking up such coal and depositing it into the tenders of locomotives occupying the dump 75 car trackage in case of necessity. The structural framing extends upwardly to the crane trackage, in a plane outside of the opening, through which the pockets are and thus gives the trolley a range of travel which 80 enables the bucket to be brought to any of the several positions named.

In order that the invention may be fully understood, I will proceed to a detailed description of the preferred embodiment thereof; reference being made to the accompanying drawing, in which—

Figures 1, 2, and 3, are, respectively, a plan view, a side elevation, and a vertical transverse section of a railway terminal embodying the several features of the invention.

1 represents a surface level track over which material, such as coal, may be brought in from any distance in standard dump cars 95 A; and 2 represents a subsurface storage bunker adapted to receive the material, by gravity, from said dump cars. Bunker 2 may be supplied with water, as, for instance, through hydrant 3 to render safe from spontaneous combustion or external ignition coal stored indefinitely therein. To remove coal from bunker 2, a grab-bucket or other lifting receptacle 4 is suspended from a crane, as, for instance, from the trolley 5 running on bridge 6 which traverses the tracks 7 and thus adapts the bucket to discharge into any one of a series of provisional containers or distributing pockets 8. Containers 8 are above a delivery track 9, which is preferably 100 on surface level or suitably connected therewith, and are adapted to deliver into a trans-

port vehicle B presented on track 9 beneath them. Vehicle B is shown as a road surface vehicle, but it is to be taken as typifying any vehicle that it may be desired to load from the pockets, and the track or way 9 is to be taken as the equivalent of a rail-equipped track if it be desired to present locomotive tenders beneath the pockets.

By having the pockets 8 overhang the storage chamber 2 as shown, surplus or overflow coal returns to the latter.

By having an electric weighing device 10 interposed in the lifting cable and adapted to be read upon the ammeter in the engineer's cage 11, the weight of material deposited into each pocket 8 can be determined in transit, and since the crane deposits in the individual pockets selectively, a record can be kept of the contents of each and render it unnecessary to weigh the load deposited into a vehicle B.

Structural framing 12-13 rises from the lateral confines of the bunker 2 and therefore from either side of the dump car trackage 1, the framing 12 being between the bunker 2 and the track 9. This framing rises not only to the level at which it supports the individual charge-pockets 8, but beyond the same at least to a level which accommodates the bridge tracks 7; and as shown more clearly in Fig. 1, the open tops of the pockets 8 extend well within the tracks 9 and the track 7 so that the bucket 4 can travel to a point above any pocket in the series; but the lower discharge ends of these pockets are on the outer side of the framing 12.

By an arrangement such as here described, the purposes of the invention can be fully realized in a simple and efficient manner, with a minimum of expenditure of power and minimum loss of time of the conveying vehicles.

Obviously, the subsurface storage bunker may be subdivided into compartments for the storage of different classes of coal. When so subdivided the partitions may be such as to admit water from one compartment to another (say, through the spacing of the partition from the bottom of the bunker) or the partitions may be tight so that water storage will be available for those classes of coal which are more liable to spontaneous combustion, while other classes are dry stored.

I claim:

1. A coaling station comprising surface-level supply trackage for coal carrying cars, a sub-surface pit of major capacity receiving coal by gravity from cars standing on said trackage, and coal distributing means comprising supports rising above said pit and trackage, open top delivery bins of minor capacity mounted on said supports at an intermediate level and a bucket handling crane surmounting said supports, over-traveling the storage pit, the cars on said supply trackage and the delivery bins; said pit and bins being offset horizontally one from the other, whereby the hoisting bucket has vertical access to said pit, to cars on said trackage and to all of said bins.

2. A coaling plant comprising a dump car trackage, a sub-surface storage bunker constructed and proportioned to confine and afford protective storage to coal in tonnage bulk, located beneath and in the direction of said trackage and receiving by gravity, into storage position, coal from dump cars on said trackage; supports rising from said bunker on either side of said dump car trackage, distributing trackage for coal receiving vehicles extending along the outside of one of said supports; a series of pockets extending along said supports, adapted to contain charges of coal, and mounted on said supports at an intermediate level thereof, said pockets having upwardly presented receiving openings on the inner side of said supports and downwardly presented delivery openings on the outer side thereof, over the distributing trackage; crane-bridge tracks mounted on said supports parallel with said series of pockets but at a level above the same, one of said tracks being in a vertical plane outside the receiving openings of the pockets; a bridge mounted on said bridge tracks adapted to be brought over any pocket in the series; a trolley on said bridge; and a bucket having elevating connections carried by said trolley and adapted to be, by said trolley, presented to bulk coal in said bunker, also to any pocket over which the bridge is standing and to any open top coal carrier occupying the dump car trackage.

Signed at Chicago, Illinois, this 15th day of December, 1921.

SPENCER OTIS.
